UNITED STATES PATENT OFFICE.

MARVIN L. ROWE, OF ALBANY, NEW YORK.

DESIGN FOR A PROPELLER.

SPECIFICATION forming part of Design No. 32,885, dated June 26, 1900.

Application filed May 7, 1900. Serial No. 15,848. Term of patent 14 years.

To all whom it may concern:

Be it known that I, MARVIN L. ROWE, a citizen of the United States of America, and a resident of the city of Albany, county of Albany, State of New York, (post-office address, No. 130 State street, Albany, New York,) have invented and produced a new and original Design for Propellers, of which the following is a specification, reference being had

10 to the accompanying drawings, forming a part thereof, in which—

Figure 1 is a rear elevation of the propeller-blade. Fig. 2 is a side elevation. Fig. 3 is a front elevation. Fig. 4 is a section along

15 the lines X X on Fig. 2. Fig. 5 is a perspective.

The leading or material feature of my design consists of two concavo-convex blades A B, arranged on opposite sides of the boss

20 C, the blades A B being each curved from the boss toward their edges a and b, respectively, farthest from the boss, and also curved in the

direction of their length, so as to pass half-way around the boss, the extreme lower ends of the blades forming the appearance of the tail 25 of a fish. The front parts a' b' of said blades extend forward of the boss C and are curved, as at a'' b'', from the tip of the blades a' b' to the boss C. There is a gradual increasing of the pitch from the front edges a' and b' of the 30 blades radially and aft—that is, to the extreme width and at the same time from the front to the rear.

Having described my invention, what I claim as new, and desire to secure by Letters 35 Patent, is—

The design for a propeller as herein shown and described.

Signed by me at Albany, New York, this

the 2d day of May, 1900.

MARVIN L. ROWE.
